Primary Examiner — Barbara Fox*Assistant Examiner* — Jane Yoon(74) Attorney, Agent, or Firm — Fitzgerald IP Law; John K. Fitzgerald, Esq.(57) CLAIM

The ornamental design for a case for toy beads, as shown and described.

DESCRIPTION

FIG. 1 is a perspective view showing the front, top and right sides of a case for toy beads showing my new design; FIG. 2 is a perspective view showing the bottom, left, and rear sides of the case for toy beads of FIG. 1;

FIG. 3 is a front view of the case for toy beads of FIG. 1; FIG. 4 is a rear view of the case for toy beads of FIG. 1; FIG. 5 is a top plan of the case for toy beads of FIG. 1; FIG. 6 is a bottom side view of the case for toy beads of FIG. 1;

FIG. 7 is a right side view of the case for toy beads of FIG. 1; and,

FIG. 8 is a left side view of the case for toy beads of FIG. 1.

The broken lines shown are included for the purpose of illustrating portions of the case for toy beads, which form no part of the claimed design.

1 Claim, 8 Drawing Sheets(56)
